UNITED STATES PATENT OFFICE.

FRANK STEAD MANTON, OF PROVIDENCE, RHODE ISLAND.

COMBINED BITT AND DECK-PIPE FOR VESSELS.

SPECIFICATION forming part of Letters Patent No. 387,894, dated August 14, 1888.

Application filed May 14, 1888. Serial No. 273,836. (No model.)

To all whom it may concern:

Be it known that I, FRANK S. MANTON, a citizen of the United States, residing at Providence, in the county of Providence and State of Rhode Island, have invented certain new and useful Improvements in Deck-Pipes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to ships' windlasses; and its object is to improve the deck-pipe or bushing through which the cable is passed into the chain-locker below.

As ordinarily constructed, the deck-pipe 20 consists of a short cast-iron tube having a flange around one end. It is fitted into a hole cut in the deck and is calked to make a tight joint where it comes in contact with the deck-planks. The surface of the casting is often 25 rough and uneven, and consequently does not fit tightly into the hole, rendering it difficult to calk it satisfactorily.

My improved deck-pipe is cast in one and the same piece with the windlass-bitt. The 30 bottom of the combined bitt and deck-pipe is planed off true and smooth, and the surface of the deck is similarly prepared, so that the two surfaces will fit closely together. A coat of cement—such as white lead or tar—on the bottom of the bitt around the deck-pipe makes a 35 tight joint when the bitt is bolted down to the deck.

In the drawings, Figure 1 represents in perspective a starboard-side bitt provided with 40 my improved deck-pipe, and Fig. 2 is a side elevation of the same with the deck and deck-pipe in section.

The windlass-bitt A is a cast-iron one, similar to that shown and described in United States 45 Patent No. 197,040, granted to me November 18, 1877. It is provided with a bracket, B, for the attachment of the clearing-guard, and is surrounded by a flange, a, by means of which it is bolted to the deck. The shaft of the windlass is received in the bearings D. Adjacent to

the windlass-bitt, on the same side of it as the bracket B and lying with its axis in the vertical plane of the axis of the windlass-shaft, is the deck-pipe E, which consists of a short tube rising from the flange a of the side bitt, 55 said flange being considerably widened for a portion of its length to surround the deck-pipe on all sides, as shown. A web, E', unites the side bitt and the deck-pipe and stiffens the latter very considerably. The pipe is preferably 60 elliptical in plan, and is provided on its after half with an internal bolster, e, to receive the friction of the cable and prevent it from catching on the edge of the deck-pipe as it enters the chain-locker.

A hole, F, is cut in the deck of the vessel to register with the deck-pipe. Before the bitt is placed in position, the under surface of the flange a is planed smooth, and a coat of white lead is applied, which makes a water-tight 70 joint all around the deck-pipe when the bitt is bolted down.

Having thus described my invention, what I claim, and desire to secure by Letters Patent, is—

1. A cast-iron windlass-bitt provided with a deck-pipe integral therewith, substantially as described.

2. A cast-iron windlass-bitt having a laterally-projecting flange and a deck-pipe rising 80 from said flange and integral therewith, substantially as described.

3. The cast-iron windlass-bitt A, provided with the flange a, the deck-pipe E, rising from said flange, and the web E', uniting the deck-pipe and the bitt, substantially as described.

4. The combination, with the deck of a vessel, having the hole F, of a cast-iron windlass-bitt provided with a deck-pipe integral therewith and registering with the hole, the under 90 surface of the bitt and deck-pipe being planed smooth and coated with cement, substantially as described.

In testimony whereof I affix my signature in presence of two witnesses.

FRANK STEAD MANTON.

Witnesses:

EDWIN H. WHITNEY,
GEORGE METCALF.
